UNITED STATES PATENT OFFICE.

WILLIAM H. COX, OF ATLANTA, GEORGIA, ASSIGNOR TO HUGH E. SESSIONS, OF COLUMBIA, SOUTH CAROLINA.

COTTON-SEED LINTER.

1,220,959.

Specification of Letters Patent. Patented Mar. 27, 1917.

Application filed July 28, 1914. Serial No. 853,598.

To all whom it may concern:

Be it known that I, WILLIAM H. Cox, a citizen of the United States, residing at Atlanta, in the county of Fulton and State 5 of Georgia, have invented certain new and useful Improvements in Cotton-Seed Linters, of which the following is a specification.

The present invention relates to improvements in cotton seed linters, and is designed especially as a de-linting machine which is more facile, economical, and efficient than many types of machines of this character now in use.

15 The primary object of the invention is to improve machines of this class by means of which the lint may be more thoroughly separated from the cotton seed after having passed through the cotton gin, and to more 20 efficiently separate the lint from motes and other trash, thereby producing commercial lint of a much higher quality.

The invention consists essentially in certain novel combinations and arrangements 25 of parts by which the air is taken from in front of the linter and its passage to the linter regulated, and also in the disposition of the mote boards, as will be hereinafter described.

30 In the accompanying drawing I have illustrated one complete example of a linting machine equipped with the physical embodiment of my invention, constructed according to the best mode I have so far devised for practical application of the principles of my invention.

In the typical linting machine illustrated 40 in the drawing the casing 1 incloses the saw cylinder 2 which includes the usual gang of saws 3 passing between the ribs 4, as will be readily understood by those skilled in the art. The lint and seed are fed to the saws through the opening 5 from the hopper 6 and the float agitators 7 turn the seeds so 45 that they pass down at the front of the saw cylinder and out through the outlet opening 8 at the front of the casing.

The brush 9 revolving on its shaft 10 as indicated by the arrows carries the bristles 50 11 which contact with the cylinder 2 as usual. Preferably the brush revolves at a much higher rate of speed than the saw cylinder, and the cotton is brushed from the

teeth of the saws down toward the floor or platform 12 through the chamber or space 55 13. The draft created by the revolution of the brush is the principal medium by which the lint is drawn from the teeth of the saw cylinder, and a transversely extending plate 14 preferably of galvanized iron 60 which extends from end to end of the saw cylinder, is utilized to regulate the excess draft caused by the saw cylinder and deflect this draft down to a position within the space 13 best suited to separate the trash 65 and motes from the lint.

As before stated, the air for conveying the lint through the machine is brought in from in front of the linter. The air is brought in through the opening or doorway 70 15 in the front of the machine, and this opening or doorway is regulated as to size by means of the vertically adjustable gate or door 16, preferably of galvanized iron. Numerous ways may be adapted for guid- 75 ing the door in its movement, but as an example I have illustrated slotted guide ways as 17 at each end of the door, and the door, which carries a rack wheel 18, may be raised or lowered by rotating this wheel in 80 engagement with the stationary rack bar 19 at one side of the door. By this means the opening 15 may be regulated and the entrance of air to the casing of the machine may be governed. By locating the outlet 85 15, any lint remaining on the seeds at this point will be carried into the linting machine by the draft, and thus saved for use.

An essential element of my invention is 90 the mote board 20 which as clearly shown extends upwardly, at an angle, from the floor 12 and backward under the brush 9, passing within approximately two or three inches of the brush in actual use. At the 95 rear this board merges into the wall 21 of a flue 22 which opens adjacent the wire mesh drum 23 revolving as indicated by the arrow in proximity to the cylinder 24.

This board is preferably of galvanized 100 iron, and its location as shown prevents back draft or drafts from the rear entering the linting machine, and the presence of this mote board as thus arranged eliminates the possibility of the dust that is deposited 105 under the drum 23 from being carried back

into the lint. The operation of the machine will be evident. The loose lint, which falls in front of the opening 15 from the seeds passing through outlet 8, is carried through the opening 15 and together with the lint from the saw cylinder and brush, is passed through the flue 22 to the wire mesh drum 23, the trash, etc., falls through the space 13, some of it striking the angular portion 10 of the mote board 20 and being deposited on the platform 12, and the dust falls below the wire mesh drum 23.

The loose lint from the seeds as they fall through the outlet 8, which ordinarily settles all over the lint room and linters and is swept up as trash and burned, is properly taken care of by passing through the opening 15 and is made into a merchantable product, and the result is that the linters 20 and lint room are almost free from dust and flying particles of lint. By the utilization of my invention I not only secure a better and cleaner quality of lint, but more lint is secured because of the presence of the draft regulator and mote board 20.

Having thus fully described my inven-

tion, what I claim as new and desire to secure by Letters Patent is:—

1. The combination with a linting machine including the saw cylinder and brush 30 and casing therefor, of a mote board forming a space below these elements within the casing, adjustable means for permitting entrance through the front of the casing of air to this space, and a transverse deflector plate 35 between the cylinder and air inlet.

2. The combination in a linting machine with the saw cylinder, brush and casing, of a mote board forming a space below the cylinder and brush and located below the 40 brush to form a passage, said casing having an opening in its front and an adjustable gate for regulating said opening, and a transverse deflector plate between said opening and the cylinder. 45

In testimony whereof I affix my signature in presence of two witnesses.

WILLIAM H. COX.
